United States Patent Office

Des. 185,896
Patented Aug. 11, 1959

185,896

TIRE

Rush M. Johnson, Jr., Wadsworth, Ohio, assignor to The
B. F. Goodrich Company, New York, N.Y., a corpora-
tion of New York

Application December 15, 1958, Serial No. 53,766

Term of patent 14 years

(Cl. D90—20)

Fig. 1 is a perspective view of a tire showing my new design, it being understood that the tread portion shown is repeated throughout the circumference of the tire and the buttress design shown is repeated throughout the circumference of the sidewall, the opposite side of the tire being substantially like the side shown; and

Fig. 2 is a perspective view of a section of the tire on an enlarged scale, the portion of the side shown being opposite the side appearing in Fig. 1.

claim:

The ornamental design for a tire, substantially as shown and described.
